SADIRON

Walter K. Tavender, Haworth, N. J.

Application February 17, 1934, Serial No. 711,687

7 Claims. (Cl. 38—77)

My invention relates to electrically heated steam irons and the principal object of my invention is to provide a steam iron construction comprising a base portion having a plurality of steam 5 passage bores drilled therein to form steam passages so arranged that steam may be appreciably superheated in certain of the passages before it is introduced into other passages from which it is discharged at the pressing surface of the iron, 10 and means for regulating and controlling a flow of steam between such superheating and other passages.

Another object is to provide a sad iron construction having primary means, comprising a 15 steam chest, for superheating steam, secondary means for further superheating or maintaining the temperature of the steam before it is discharged from the iron, and means for regulating and controlling a flow of steam between said primary and secondary means.

A further object is to provide a steam iron having a manually operable valve with improved adjustable means for limiting the movements of the valve, thereby insuring against an excessive flow 25 of steam from the iron and permitting the valve to be held open a fixed degree to allow a constant and steady minimum flow of steam thru the iron.

A further object is to provide improved means 30 for regulating a flow of steam into the iron. A further object is to provide convenient means for cleaning out the steam passages of the iron, and other and further objects will appear from the 35 following specification.

Referring to the drawings which form a part of this specification:

Figure 1 is a side elevation of a steam iron embodying the features of my invention and

Figure 2 is a plan view thereof.

Figure 3 is a view in partial section taken on line 3—3 of Figure 2 and illustrates the structure of the manually operable valve employed to regulate and control a flow of steam thru the iron, as 45 well as the adjustable means for limiting the movements of the valve.

Figure 4 is a fragmental view in partial section taken on line 4—4 of Figure 2 and further illustrates the adjustable means employed to limit the movements of the valve.

Figure 5 is a sectional view taken on line 5—5 of Figure 2.

Figure 6 is a sectional view taken on line 6—6 of Figure 5.

Figure 7 is a sectional view taken on line 7—7 of Figure 6.

Figure 8 is a plan view of the one piece base portion of the iron.

Figure 9 is a sectional view taken on line 9—9 of Figure 8, and

Figure 10 is a sectional view taken on line 10—10 of Figure 9 and illustrates the arrangement of the bores which form the principal steam 10 passages in the base of the iron.

Figure 11 illustrates the restriction pieces employed to regulate a flow of steam into the iron.

15 indicates the base of the iron which comprises a casting having a pressing surface 16 formed on its underside and a recess formed in 15 its upper surface over the area 17 to receive an electric heating element, not shown. A steam chamber or chest 18 is cored or otherwise internally formed in the base rearward of the recess 17 and extends transversely of the butt end of the 20 base casting. A vertical wall 19 partially divides the steam chest, and the floor of the chest is slightly elevated on opposite sides of the wall 19, all as best illustrated in Figures 5 and 8.

25 A plurality of steam passages are drilled in the base casting in a plane below the steam chamber 18 and comprise a passage 20, formed by the converging bores 20^a and 20^b which extend forwardly from the butt end of the base. A similar passage 21 is formed by the converging bores 30 21^a and 21^b, and a third passage is provided by the intercommunicating bores 22^a, 22^b, 22^c, 22^d, 22^e, and 22^f. Closure pieces 23—23 etc. and 24—24 etc. plug each of the bores as illustrated in Figure 10. A plurality of small drilled steam 35 discharge outlets 25—25 etc., are drilled in the base casting and extend from bores 22^a, 22^b, 22^c, and 22^f to the pressing surface 16 of the iron. Steam inlet passage 26 and passages 27, 28, 29, and 30 are formed by drilling from the upper surface of 40 the base casting and extend in communication with the bores 20^a, 20^b, 22^a, 21^a, and 21^b, respectively. The passages 27 and 29 are plugged above the chamber 18, as illustrated, and it will be noted that the passage 28 extends thru the partition wall 19.

45 The passage 30 leads to a valve 33, the casing 34 of which is securely attached to the base unit by a screw 35 as shown in Figures 3 and 5. The valve 33 is of conventional cone construction and is operable against the resistance of a spring 36 by means of lever 37 to control a flow of steam 50 from the passage 30 into a passage 38 formed in the valve casing. The passage 38 of the valve casing is in registered communication with the

upper end of passage 28 thru which steam may be admitted to the passage bore 22^a.

From the description thus far given, it may be understood that steam entering the bore 20^a thru the inlet passage 26 will flow thru the passages 20 and 21 into the steam chamber 18. Also that steam will flow from the steam chamber thru passages 21, 21, and 30 to the valve 33 and from the valve to the pressing surface of the iron via the passages 38 and 28 and the bores 22^a, 22^b, etc., leading to the outlets 25.

A cover 40 serves to enclose the electric heating element in the recess 17 of the base, is perforate to accommodate the electric terminals connected in attachment plug 41 and carries a heat regulating switch 42. This cover, together with the iron handle 43, is securely attached to the base casting by means of machine screws 44 and 44'. An arm 45 is also secured by screw 44 and extends beneath and beyond the valve control lever 37. Mounted on the free end of the arm 45 is a pillar 46 having a pair of adjustable abutments 47 and 47' threaded thereon. The lever 37 is formed of flat resilient metal, is bowed as shown, and is normally positioned between the abutments, whereby its vertical movements may be limited. When it is not desired to use the abutments in operating the valve, the lever 37 may be sprung inwardly toward the handle to avoid striking the abutments, as illustrated in Figure 4, and may then be actuated to operate the valve throughout its entire range of movement.

The base is formed adjacent the inlet passage 26 to receive the detachable coupling of steam supply line 32, as illustrated in Figure 7. The coupling is of conventional construction and comprises nipples 50 and 51 adapted to be held together by a collar 52 which threads onto the outer end of nipple 50. Between the elements of the coupling I insert a disc or washer 55 which is perforate over a predetermined area to restrict a flow of steam entering the iron.

In use the heating element is placed in operation and a flow of steam, restricted by the perforate disc 55, is led thru passage 26 into the passage 20. In flowing thru the passage 20 the steam is initially superheated in contact with the heated passage walls and, in reversing its course at the junction of the bores 20^a and 20^b, water vapor carried by the steam is broken up and converted into steam. The steam is then led into the passage 21 thru passage 21, chamber 18 and passage 29 to obtain a further superheating and further reduction in the moisture content thereof. On reaching the end of passage 21, being the rearward end of bore 21^b, the steam flows thru the passage 30 to the valve 33 in a hot and substantially dry condition before it is introduced into the passages 38 and 28.

Positioned as described, the valve is operable to control the discharge of steam from the superheating passages rather than the introduction of steam into the iron, as has heretofore been the practice in irons of this type, and by its use the steam may be held in the superheating passages for a variable time by the operator to insure that steam flowing from the iron will be discharged in a proper condition, depending upon the character of the material being pressed. In flowing thru the passages 22^a, 22^b, etc., the temperature of the steam is maintained or further slightly superheated and discharges at the pressing surface of the iron thru the outlets 25—25 etc.

Although I have devised the chamber 18 in the

base to serve primarily as a means for conducting the steam between the superheating passages 20 and 21, I have found that, located and formed as illustrated, the chamber serves to afford substantial advantages as a steam chest or expansion chamber and provides a large area of relatively heavy hot wall in contact with the steam.

In using steam irons of this general character, it is necessary that they be operated differently in pressing different fabrics. For illustration, some fabrics scorch more readily than do others; thick fabrics require that a larger volume of steam be discharged to penetrate them than do thin fabrics; and there are many delicate cloths which are stained by any water which may condense and discharge at the pressing surface of the iron.

It is to reduce the degree of care required and to guard against costly accidents that I have provided the adjustable abutments 47 and 47' to limit the movements of the valve control lever 37, as well as the restriction pieces, such as 55, to limit the flow of steam into the iron. The abutment 47 may be adjusted on the pillar 46 and employed to hold the valve open a predetermined degree, thus providing a constant minimum flow of steam from the iron; whereas the abutment 47' may be similarly adjusted and employed to limit a maximum discharge of steam.

When the abutment stops are not used, the restriction disc 55 prevents a flow of steam into the iron greater than can be properly superheated by the iron in case the valve is held fully open. Since this, again, is a variable quantity, depending upon the volume and temperature of steam required for the particular fabric, and also upon the degree of heat being generated in the iron, I provide a plurality of restriction discs, 55, 55', etc., each having a differently sized aperture, any one of which may be inserted in the supply line coupling.

To facilitate cleaning of the steam passages, I have provided removable closure pieces which thread into certain of the bores, such as the Allen head screws 24 illustrated in Figure 10, the closure pieces 23 being the usual permanent plugs. To clean out the passages, a fluid detergent or boiler compound is introduced into the passages and thereafter the pieces 24 are removed and the fluid evacuated.

It will be noted that the base 15 extends rearwardly of the cover 40 and that the valve casing 28 is securely mounted on the extended portion of the base. Also that the steam line coupling attaches at the top of the extended base portion. I have found this of advantage over the usual arrangements in which the valve or steam line coupling is attached or connected to the butt end of the base portion because it provides a sturdier construction in which overhanging parts are eliminated.

Having thus described my invention, I claim:

1. A steam iron comprising a base portion formed with a pressing surface on its underside and a plurality of steam discharge outlets formed in said base portion and extending to the pressing surface thereof, means for conducting steam thru the iron to said outlets, and a valve for controlling a flow of steam thru the iron, a lever for manually operating said valve, and adjustable means for limiting movement of said lever; said lever limiting means comprising a pillar carried by the iron and extending transversely

of said lever and an abutment on said pillar in the path of lever movement, said lever comprising a strip of resilient metal adapted to be sprung out of its normal path to avoid said abutment.

5. 2. A steam iron comprising a base portion formed with a pressing surface on its underside and a plurality of steam discharge outlets formed in said base portion and extending to the pressing surface thereof, means for conducting steam thru the iron to said outlets, and a valve for controlling a flow of steam thru the iron, a lever for manually operating said valve, and adjustable means for limiting movements of said lever; said lever limiting means comprising: a pillar 10 carried by the iron and extending transversely of said lever, and a pair of abutment pieces adjustable on said pillar on opposite sides of said lever in the path of lever movement; said lever comprising a strip of resilient metal adapted to be sprung out of its normal path to avoid said 15 abutment pieces.

3. A steam iron comprising a base formed with a pressing surface on its underside, a heater carried by the iron above said pressing surface 25 and a cover overlying and housing the heater, said base having passage means formed therein for conducting steam to said pressing surface and a valve for controlling a flow of steam therethru, said base being extended rearwardly 30 of said heater and cover, and said valve being mounted on the rearwardly extended portion of the base.

4. A sad iron comprising a base portion formed with a pressing surface on its underside, a heater carried by the iron above said pressing surface, said base portion having two steam passages formed therein each extending forwardly from the rear of the iron and returning rearwardly, means for connecting said passages in series, 40 said base portion having a third passage formed therein and a plurality of steam discharge outlets extending from said third passage to said pressing surface, and means comprising a valve for conducting steam from the last passage in series into said third passage, said passages extending longitudinally in the same horizontal plane.

5. A steam iron comprising a base formed with

a pressing surface on its underside, a heater carried by the iron above said pressing surface and a cover overlying the heater, said base having passage means formed therein for conducting steam to said pressing surface and a valve for 5 controlling a flow of steam therethru, said base extending rearwardly of said heater and cover and said valve being mounted on the rearwardly extending portion of the base, a lever for manually operating said valve extending forwardly 10 over said cover, a pillar extending above the cover transversely of said lever, and an abutment on said pillar in the path of lever movement, said lever comprising a strip of resilient metal adapted to be sprung out of its normal path to avoid said 15 abutment.

6. A sad iron comprising a base portion formed with a pressing surface on its underside, a heater carried by the iron above said pressing surface, said base portion having a plurality of steam 20 passages formed therein and extending longitudinally in the same horizontal plane forwardly from the rear of the iron and returning rearwardly, one of said passages being an outlet passage, a plurality of steam discharge outlets 25 formed in the base portion and extending from said outlet passage to the pressing surface, means for connecting the other passages in series, and means comprising a valve for conducting steam from the last passage in series into said outlet 30 passage.

7. A sad iron comprising a base portion formed with a pressing surface on its underside, a heater carried by the iron above said pressing surface, said base portion having a plurality of steam 35 passages formed therein and extending longitudinally in the same horizontal plane forwardly from the rear of the iron and returning rearwardly, one of said passages being an outlet passage, a plurality of steam discharge outlets 40 formed in the base portion and extending from said outlet passage to the pressing surface, means comprising a chamber near the rear end of the base portion for connecting the other passages 45 in series, and means comprising a valve for conducting steam from said chamber into said outlet passage.

WALTER K. TAVENDER.
